UNITED STATES PATENT OFFICE.

ALEXIS B. DAVIS, OF ST. LOUIS, MISSOURI.

TOP-BRACE FOR BUGGIES.

SPECIFICATION forming part of Letters Patent No. 286,272, dated October 9, 1883.

Application filed April 27, 1883. (No model.)

To all whom it may concern:

Be it known that I, ALEXIS B. DAVIS, of the city of St. Louis, in the State of Missouri, have invented a certain new and useful Improvement in Top-Braces of Buggies, &c., of which the following is a full, clear, and exact description, reference being had to the accompanying drawings, forming part of this specification.

10 To My improvement applies to the jointed braces that extend from bow to bow to hold them asunder.

The scope of the invention is set forth in the claim.

15 Figure 1 is a side view of a buggy-top with part of the cover removed, showing my improved brace between the rear bow and the low next to it. Fig. 2 is a view of the top folded back. Fig. 3 is an enlarged side view 20 of the improved brace extended; and Fig. 4 is a similar view, except that the brace is folded. Fig. 5 is an enlarged top view of the brace extended. Figs. 6 and 7 are details, showing the construction of the brace-joints.

25 A is the buggy-seat. B B' B² B³ are, respectively, the first, second, third, and fourth bows of the top, (beginning at the front.) C is the top-prop pin, and D the top-prop brace. E is the brace extending from the first to the third 30 bow to hold them asunder. These parts have the usual construction, and are outside the top, being connected to the seat and bows by pins projecting from the same, so that the braces are outside the plane of the bow sides.

35 The brace F is in the plane of the sides of the bows B² and B³, and is concealed between the cover G and the cover-lining H, except as to the handle F', which can be seen below the

edge of the cover-lining, so as to be easily reached. This brace F has the usual rule-joint, I, except that the joint is made by casting a pintle-pin, J, upon one member of the brace, which passes through a hole, F'', in the other member, and is secured by riveting the end. Pintle pins J' are also cast on the ends 40 of both members, which pass through hinge-holes L' in the bracket-lugs K and L, by which the ends of the brace F are connected to the bows B² and B³, respectively. The lug K is attached by screws or rivets *k* to the rear edge 45 of the bow B², and the lug L is similarly attached to the front edge of the hind bow, B³. The construction is such that the brace extends very little, if at all, beyond the inner or outer face of the bows, (being in the same plane 50 as the parts of the bows to which it is attached.) Thus it causes no projection of the top or cover G, nor of the cover-lining H, and these parts form no obstruction to its movement in 55 extending it or folding it.

60 My improvement is shown applied to the bows B² and B³. It is obvious it may be applied to the other bows, if desired.

I claim as my invention—

65 A top-brace having two members, F, one member having two pintles cast thereon and the other member having a single pintle and handle cast thereon, and an eye to engage the inner pintle of the other member, in combination with lugs having eyes and secured to 70 the inner edges of the bows, as set forth.

ALEXIS B. DAVIS.
